METHOD OF APPLYING DECORATIVE INDICIA TO ARTICLES

Harry H. Scharfman and Martin Kamen,
Chicago, Ill.

Application January 16, 1935, Serial No. 2,026

1 Claim. (Cl. 41—35)

The present invention relates to a method of applying decorative indicia to articles, and more particularly to articles or objects which may be carried in pockets or purses of the owners.

5 The present invention, although not limited thereto, will be herein described in connection with a method of applying decorative indicia to cylindrical articles, such as pencils and fountain pens.

10 Many owners of small articles, such as pencils, pens, vanity cases and the like are desirous of having identifying or decorative indicia applied to such articles for identification or decorative purposes.

15 Such articles as manufactured and sold at retail are oftentimes attractively finished and made of materials upon which it is impossible to apply identifying or decorative indicia without destroying the appearances of such articles.

20 The present invention has, therefore, the provision of a method of applying decorative or other indicia to articles in an expeditious and economical manner, whereby the finished article is enhanced in appearance.

25 Generally speaking, the method of the present invention contemplates the application of the indicia, such as a photograph, a name, initials or any other suitable matter, to the article in a recess or undercut made in the article and then overlaid by a transparent cover which is shaped to conform to the contour or shape of the article adjacent the recess or undercut thereby producing a pleasing finished article.

30 The accompanying drawing illustrates a method 35 of carrying out the principles of the present invention, and the views thereof are as follows:

Figure 1 is an elevational view of a pencil having decorative indicia, such as initials thereto applied, in accordance with the principles of the 40 present invention.

Figure 2 is an elevational view of a fragmental portion of a pencil showing an undercut or recess formed in it for receiving the indicia and protective covering.

45 Figure 3 is an elevational view of a backing member which may be employed in carrying out the method of the present invention.

Figure 4 is a view of decorative indicia, in the 50 present instance, the initials "A. J."

Figure 5 is a view of the transparent covering member.

Figure 6 is a view of the backing, the decorative 55 indicia matter and the covering member assembled as a unit prior to application to the article,

and which constitutes one manner of carrying out the present invention.

Figure 7 is an enlarged transverse sectional view taken through a cylindrical article showing the decorative indicia as applied to it in accordance 5 with the principles of the present invention, with the relative size of the parts exaggerated for clearness.

Figure 8 is a view similar to Figure 7 with the inserted matter shaped to conform to the shape or 10 contour of the article adjacent the applied matter.

The drawing will now be explained.

Illustrated in Fig. 1 is a pencil A of a well known type. This pencil has applied to it the decorative 15 indicia designated generally as B of the present invention.

In carrying out the present invention, there may be utilized a backing member 1 of any suitable material, although it is preferably desired to 20 use a casein product for this purpose. The decorative indicia such as a photograph, initials, or other suitable matter is arranged on a piece of paper or other suitable material. The indicia in the present instance comprises the initials "A. 25 J." It is to be understood that the use of the initials for illustrating the decorative matter of the present invention has been chosen for convenience in drawing although it is intended to employ photographs, or other indicia as well as initials, names or the like.

A transparent cover 3 which may be of glass, celluloid, or a nitro-cellulose derivative is provided which preferably is of slightly greater width than the backing member 1.

35 In applying the decorative indicia of the present invention to an article, such for instance as the pencil A, there is formed in the article a recess or undercut 4, fashioned in any suitable manner. The shape of such recess or undercut 40 is such as to receive the backing member 1, when employed, and the cover member 3, to eliminate any unsightly joints or spaces.

One method of practicing the present invention is to cement or otherwise secure the backing member 1 in place in the undercut 4. Atop this backing member 1 is then applied the decorative indicia 2, cemented or otherwise secured in place, and over the indicia is applied the transparent cover member 3. The cover member 3 is cemented to 45 the backing member 1 by cement 5 which is applied along the margins of the backing member 1. Preferably the width of the decorative indicia matter 2 is less than the width of the backing member 1 so that the assembled parts prior to 50 55

shaping is that illustrated in Figure 6. After the parts have been assembled as described, the parts are then shaped in any suitable manner so as to conform to the contour or shape of the article adjacent the recess or undercut 4, the finished article having the appearance shown in Figs. 1 and 8.

Another manner of carrying out the method of the present invention is to assemble the backing member 1, the indicia 2 and the cover member 3 in superposed relation, cementing these parts together, and then applying the assembly as a unit to the undercut or recess 4 of the article A. Fig. 6 illustrates the assembly of these members prior to application as a unit to the article.

The appearance of the applied assembly is the same as that where the various members are separately applied as heretofore described and as illustrated in Fig. 7 in exaggerated size relation. After the unit has been assembled and suitably secured as by cement and placed in the recess or undercut 4, it is shaped to conform to the surface of the article adjacent such recess or undercut.

It will be understood that the present invention provides a novel method of readily applying decorative or other indicia to articles in a manner which produces a pleasing finished item, and in which the manner of application is expeditious and economical.

If desired, the indicia 2 and the backing 1 might be made in contrasting colors to enhance the appearance of the finished article.

When a photograph is used as a decorative indicia, in place of the initials of the indicia 2, the appearance, of course, of the finished article will show the photograph through the transparent cover member 3, in the same manner as the initials appear in the finished article, Fig. 1.

While the present invention has been described in connection with the application of decorative indicia to a cylindrical article, such as a pen or pencil, it is to be understood that the invention is not thereto limited, as it may be as readily employed in connection with the application of

decorative or other indicia to other articles of different and other shapes.

In securing the backing member 1, the indicia 2, and the cover member 3, in assembled relationship, the various members are pressed together until the cement or other securing material sets, whereupon the article is then ready for shaping as described.

While the cover member 3 has been illustrated and described as being slightly greater in width than the backing member 1 and the indicia 2, it is to be understood that these various members may be of the same width, if desired.

The shaping of the members is followed by or includes polishing of the transparent cover member 3.

The decorative indicia of the present invention may be readily applied to cigarette holders, cigarette cases, vanities or other articles of like nature, with equal success.

We are aware that many changes may be made and numerous details of construction may be varied through a wide range without departing from the principles of this invention, and we, therefore, do not purpose limiting the patent granted hereon otherwise than necessitated by the prior art.

The invention is claimed as follows:

The method of applying decorative indicia to a cylindrical object, such as the barrel of a fountain pen, so as to present a continuous smooth surface to the fingers of the user of the pen, and to also protect the indicia against wear incident to the use of the pen, said method comprising the steps of removing a portion of the outer surface of the object to provide a depressed area, then placing a thin member carrying indicia in the depressed area to still leave a depressed area, and then superimposing a layer of transparent material on said member to fill said depressed area and present a surface of the object continuous with the contiguous smooth surface thereof, and made integral with said object.
